UNITED STATES PATENT OFFICE

2,037,730

ELECTRIC SWITCH

William K. Mason, Malden, Mass., assignor, by
mesne assignments, to American Electrical
Corporation of Massachusetts, Boston, Mass.,
a corporation of Massachusetts

Original application May 9, 1929, Serial No.
361,682. Divided and this application January
12, 1934, Serial No. 706,388

3 Claims. (Cl. 200—8)

This application is a division of my co-pending application Serial No. 361,682, filed May 9, 1929.

The invention relates to an electric switch, it being an object of the invention to provide a switch whereby a plurality of contact points may be successively connected, the switch structure being simple, inexpensive and efficient in operation.

For a more complete understanding of the invention, reference may be had to the description thereof which follows and to the illustration of certain embodiments thereof on the drawing, of which

Figure 1 is a rear perspective view of a switch embodying the invention.

Figure 2 is a fragmentary section on the line 2—2 of Figure 1.

Figure 3 is a perspective view of a portion of a key-operated switch embodying the invention.

Figure 4 is a perspective view of a sector plate to cooperate with the part shown in Figure 3.

Figure 5 is a fragmentary front elevation of a panel on which a key-operated switch is mounted.

Figure 6 is a sectional view on the line 6—6 of Figure 5.

The switch illustrated in Figures 1 and 2 consists essentially of a suitable base 10 of insulating material in which is journaled a shaft 11. A sector-shaped plate 15 is mounted on the rear end of the shaft 11 as by a screw 16 so as to rotate with the shaft, the plate 15 being preferably spaced from the base 10 as by a washer 17. The plate 15 is provided with an arcuate edge 18, the center of curvature of which is concentric with the shaft 11 so that the curved edge 18 moves upon itself when the plate 15 is revolved about the shaft 11. Contact elements 22 are provided for engagement with the edge 18 of the plate 15. These contact elements may each be supported by a suitable post 21 secured to the base 10, any desired number of contact elements 20, for which there is room on the base, being employed. It is ordinarily desirable that the sector plate 15 be not greater than a semi-circle and that the contact elements 20 be arranged in arcuate series about the shaft 11 as a center so as to occupy less than a semi-circle, so that the sector plate 15 can be out of contact with all of the elements 20 when in one position, and in contact with all of the elements 20 when in another position. It is evident that the sector plate 15 can be moved into additive contact with the several elements 20 in succession. Each element 20 consists preferably of a hollow cylindrical member of resilient material such as copper or brass. The element may be cut

from a tube of such metal or may be formed, as indicated on the drawing, by curling a strip of resilient metal so that the ends overlap as shown. Each such element may be attached to its post 21 as by a screw 22 or by any other equivalent means. The point of attachment of each element to its post is preferably on the side remote from the side 16, each element being so arranged as to project a movable portion into the path of movement of the edge 18 of the plate 15, so that, as the plate 10 revolves about the axis of the shaft 11, the edge portion thereof engages successively the several elements 20 and moves the engaged portions radially outward so that they ride on the edge 18 and maintain resilient contact therewith. Since the edge 18 rubs against the side of each element 20 against the resilient pressure of the element, both the edge and the contact portions of the elements are kept so that a good electrical contact is maintained. For operation of the switch, a suitable finger knob 25 may be mounted on the forward end of the shaft 11, a spring washer 26 being provided, if desired, to furnish a certain amount of frictional resistance to rotation of the shaft 11 and plate 15 so that the plate will remain in any position to which it is turned. The screws 22 may be employed, if desired, as binding posts to connect wires to the respective contact elements 20. The plate 15 may be either a bridging conductor to connect the several elements 20 together or it may be connected to a wire by the use of the screw 16 as a binding post so that the wire connected to the plate 15 may be successively and additively connected to the wires leading to the several elements 20.

Figures 5 and 6 illustrate an embodiment of the invention which is operable by a key. To this end a lock barrel 30 is mounted on a base 31 which is preferably of insulating material. This form of switch is especially desirable where the switch is mounted inside of a cabinet, which, as shown, may have a steel wall 32 to protect the contents from unauthorized access or tampering. The barrel 30 is provided with a suitable key slot 33 into which a key may be introduced for the purpose of revolving an arm 35 which carries a pin 36 eccentric with respect to the axis of rotation of the arm 35. Mounted on the base 31 are one or more posts 21 each of which carries a resilient contact element 20 in a manner hereinbefore described. A sector plate 40 is suitably supported on the base 31 as by an insulating element 41 carried by pillars 42 which are secured to the base 31. A bolt or screw 43 projects loosely through an aperture 44 in the plate 55

49 so that the plate can rotate about an axis co-
incident with or parallel to the axis of the bolt.
The bolt preferably fits snugly in the aperture
44 so that the rotation of the plate thereon is
5 against a suitable amount of frictional resist-
ance. The bolt 43 is arranged coaxially with the
axis of rotation of the arm 35. The pin 36, as it
revolves around the axis of rotation of the arm
35, is adapted to engage the radial portions of
10 the sector plate 40. If desired, suitable notches
46 may be provided in these radial edge portions
to receive the pin 36. The arc subtended by
the plate 40 is preferably such that a complete
15 revolution of the arm 35 about its axis will move
the plate 40 into contact with all of the contact
elements 20 which are mounted on the base 31,
and a complete revolution of the arm 35 in the
opposite direction will move the plate 40 out of
20 contact with all of the elements 20. Since the
plate 40 is a current-carrying part, it is prefer-
ably insulated from the steel wall 32 of the cabi-
net by any suitable means such as a conventional
insulating bushing 50 or by making the pin 36
25 of insulating material.
25 It is evident that various modifications and
changes may be made in the embodiments herein
illustrated and described without departing from
the spirit or scope of the invention as defined in
the following claims.

30 I claim:

1. An electric switch comprising a member hav-

ing an arcuate edge, said member being rotatable
about the circle center of the arc of said edge,
a plurality of posts mounted in arcuate series
about said center, a contact element carried by
each said post to project into the path of said
5 arcuate edge, each element comprising a hollow
cylinder of resilient metal surrounding a post
and attached thereto at a point thereon remote
from said circle center.

2. An electric switch comprising a thin disk 10
sector rotatable in its own plane about the cir-
cle center of the sector, a plurality of posts
mounted in arcuate series about said center be-
yond the outer edge of said sector with their
axes substantially parallel to the axis of rota- 15
tion of said disk sector, and a deformable metal
cylinder attached to each said post, each said
cylinder being engageable by the outer edge of
said sector as it rotates about said center.

3. An electric switch comprising a member hav- 20
ing an arcuate edge, said member being rotatable
about the circle center of the arc of said edge,
a plurality of posts mounted in arcuate series about
said center, a contact element carried by each
said post to project into the path of said arcuate 25
edge, each said element comprising a strip of
resilient metal bent into cylindrical form with
overlapping end portions secured to one of said
posts, and means operable to rotate said member.
